WITNESS:

UNITED STATES PATENT OFFICE.

WILLIAM K. PINNELL, OF SEDALIA, COLORADO.

THERMOSTATIC CIRCUIT CLOSER.

Application filed May 25, 1922. Serial No. 563,547.

To all whom it may concern:

Be it known that I, WILLIAM K. PINNELL, citizen of the United States, residing at Sedalia, in the county of Douglas and State 5 of Colorado, have invented new and useful Improvements in Thermostatic Circuit Closers, of which the following is a specification.

This invention relates to an electrically 10 operated alarm for brooders, and the object is to provide, in connection with suitable mounting means, a thermostatic wafer, and particular means for completing a circuit and sounding an alarm when the temperature rises above a specified point, or falls 15 below that point.

A further object is to provide a stem for 20 mounting the wafer referred to, the stem having one end thereof connected with the circuit, the opposite end cooperating with a spring held and adjustable contact when the wafer expands, and said stem carrying an element for engagement with an additional spring held contact member, when 25 the wafer contracts, due to a drop in temperature below the point determined upon before setting an adjustable device associated with the additional contact element.

With the foregoing and other objects and 30 advantages in view the invention consists in the novel construction and arrangement of elements described and claimed, it being understood that modifications may be made within the scope of the claim without departing from the spirit of the invention.

In the drawings, Figure 1 shows the operative elements of the device and the mounting means, the view being chiefly in elevation, with parts in vertical section; Figure 2 is a view in elevation showing a vertical stem for the wafer, slotted for an element designed to prevent rotation of the stem; Figure 3 is a view in vertical section and elevation, of the contact mechanism and wafer; Figure 4 is a similar view of another form; Figure 5 is a top plan view of the contact mechanism of Figure 3, the upper housing being in horizontal section.

In carrying out my invention, I provide 50 suitable mounting means, such as a frame 10 formed of dry wood, and preferably of hard wood. The elements of the frame may be connected by bolts or screws 11, the heads and nuts being countersunk.

55 A thermostatic wafer is designated 14 and the expansion thereof causes the stem

or rod 15 to come into engagement with the contact element 16 carried by the flat spring 17. This spring is mounted in a metallic block 18 carrying a binding post 60 19 and including an arm 20 through which an adjusting screw 21 passes. This screw is designed to control the space between the end of rod 15 and contact element 16. The, upper end of the rod is guided by metallic 65 plate 23 mounted on the dry wood insulation of the frame.

The stem 15 comprises a portion of an electric circuit and the separate lower end 15' extends through plate 24, and a binding 70 screw 25 provides means for connection with wire 26 leading to battery 27, bell 28 and binding post 19. The circuit is completed through bracket or block 18, spring 75 17, contact element 16, thence to stem 15. 75 This circuit is energized upon the expansion of wafer 14, due to excessive heat. The complete circuit may be traced as follows: battery 27, wire 27', bell 28, binding post 19, bracket 18, spring 17, contact 16, upper 80 stem 15, including portions 42, 43, wafer 14, lower stem 15', elements 25, 26, to battery 27.

A contact element 30 cooperates with contact element 31 mounted on the spring 32 85 secured to bracket 33. This bracket carries an adjusting screw 34 for controlling the position of the spring and contact 31, and also carries a binding post 35 connected with wire 36 leading to binding post 19. 90

If the temperature falls below the point desired, a circuit is completed through elements 30, 31, lower stem 15', post 25, wire 26, battery 27, wire 27', bell 28, wire 29, post 19, wire 36, post 35, bracket 33, spring 95 32, and the contact elements specified. The circuits are normally open, the adjusting screws 34 and 21 being set at the points required to retain the alarm inactive so long as the thermostatic wafer 14 neither expands nor contracts beyond the prescribed limits.

A transverse brace is designated 38, and a coiled spring 39 surrounds the stem, in the manner shown. The spring bears 105 against plate 40 and against washer 41, the latter being carried upon the upper end of square portion 42 of the stem which is non-rotatable with reference to element 38, but slides therethrough, and carries contact 110 element 30. The lower end 43 is secured to wafer 14, so that the contraction of the

- wafer allows spring 39 to expand, and the contact element 30 to move downwardly into engagement with contact 31. A socket member 14' on the lower side of 5 the wafer loosely engages the upper rounded end of stem 15', this socket member or seat having a concave recess, and electrical connection being made by the pressure of spring 38.
- 10 In the form of the device shown in Figure 2, rounded stem 45 is slotted longitudinally, or vertically, and a transverse bar or element 46 extends through the slot and prevents rotation of the stem, maintaining 15 the contact elements in alinement.
- 15 In the form shown in Figure 3, square stem 47 passes through a square opening in plate 47' on the frame or housing 48, the latter being of any suitable material or construction. The upper offset end 50 of the 20 stem cooperates with the upper adjustable resilient contact element 51 mounted on block 52 (of metal), or with lower resilient contact element 53, also on this block. The 25 block is apertured and is slidable on pins 54, springs 55 abutting the base 54' and block 52 and normally forcing the block upwardly. Adjusting nut 56 on screw 57 limits the movement of the block in an upward direction. The base is insulated and 30 mounts binding post 54''. The circuit is through either resilient contact element and the stem, as before. Hinged cover 58 protects the contact members.
- 35 The upper resilient contact member is independently adjustable by screw 59.
- The further form illustrated in Figure 4 includes an insulated bridge-like element 60 having a binding post 61 connected 40 therewith and mounting resilient contact elements 62, 63 controlled by adjusting screws 64, 65. The offset end 66 of square stem 67 cooperates with these contacts as before described. In the several forms, the wafer, of any standard type, is designed 45 to be included in the circuit, details usually being omitted in the disclosure of the modifications, if referred to in connection with the first form.
- 50 What I claim is:
- In a device of the class described, a thermostatic element, a stem controlled thereby and including a device extending laterally from the stem, a plurality of contact members between which said device is movable 55 upon the expansion or contraction of the thermostatic device, a vertically movable element for mounting the contact members, guiding devices for said vertically moving element, one of said devices last named 60 being threaded and all of these guiding devices passing loosely through the vertically movable element, resilient means for imparting thrust to said element, and an adjustable device engaging the threaded 65 guiding device for limiting the extent of movement of the vertically movable element under resilient action and varying the distance between one of said contact elements and the device on the stem, means on the 70 vertically movable element for independently adjusting the other contact element, and means for completing a circuit through said stem and either of the contact elements and the mounting means thereof. 75

In testimony whereof I affix my signature.

WILLIAM K. PINNELLY.
